CATALYTIC CONVERSION OF HYDRO-CARBONS

Charles L. Thomas, Chicago, Ill., assignor to Universal Oil Products Company, Chicago, Ill., a corporation of Delaware

Application May 17, 1939, Serial No. 274,132

3 Claims. (Cl. 196—10)

This invention relates to the catalytic conversion of hydrocarbons produced by the distillation of heavy hydrocarbonaceous materials, and more particularly, distillates which are vaporizable without substantial decomposition.

More specifically, the invention concerns the conversion of hydrocarbons by means of specially prepared catalysts into gasoline and desirable gaseous products together with the treatment of such gasoline and gaseous products to produce increased yields of motor fuel of premium quality. In general, the charging stocks are distillates from petroleum sources, although hydrocarbons produced from coal tars, shale oils, and the like, may be included within the intended scope of the invention.

The art of producing gasoline and gas by thermal cracking of petroleum oils is extensive and because of the large amount of investigation has been developed to the point where the principles involved are fairly well understood. The principles of catalytic conversion of hydrocarbons, and more specifically, the catalytic cracking of high-boiling hydrocarbon fractions from petroleum to produce gasoline and gas are not so well understood. Such explanations as have been set forth are largely empirical and a discussion of these reactions, is therefore, best confined to a factual basis.

In one specific embodiment the present invention comprises a method for converting hydrocarbon fractions into high yields of gasoline by contacting said fractions in vaporous form with a cracking catalyst at conditions adequate to effect catalytic cracking, separating the gasoline and gas, recirculating a portion of the unconverted oil to the catalytic cracking step, separating the gasoline into a low-boiling and a high-boiling fraction, separating the gas into a plurality of fractions, subjecting a fraction comprising essentially butane-butene hydrocarbons to polymerization, recovering the portion of the polymer comprising essentially octenes, returning a portion of polymer boiling above the octene fraction to the catalytic cracking step, combining the octene polymer with the aforementioned low-boiling fraction of catalytically cracked gasoline and a portion of the hydrogen-containing gas from the catalytic cracking step, contacting this mixture with a hydrogenating catalyst at hydrogenating conditions, recovering the normally liquid hydrogenated product, combining the residual gases from the aforementioned polymerization step with the gaseous fraction from the catalytic cracking step which comprises essentially pro-

pane-propylene hydrocarbons, subjecting said mixture to polymerization, recovering the polymerized products, and blending controlled portions of the products of the various steps to form a gasoline of high octane number and susceptibility to tetraethyl lead.

Many catalysts have been proposed to assist the conversion of distillates into gasoline and gas. Among these are certain types which promote, as the predominating reaction, the formation of gas rather than gasoline. Such catalysts include the reduced metal catalysts, such as nickel and iron and their ores. These catalysts are, furthermore, subject to poisoning by sulfur compounds and tend to produce coke-like materials which deposit as a film around the catalysts and render them inactive. Other types of catalysts promote dehydrogenation reactions rather than true cracking, and as a consequence, the character of the gases and the antiknock properties of the gasoline produced are considerably different than those which are used in the present invention.

The present process conveniently utilizes more or less refractory cracking catalysts which are produced by the chemical treatment of naturally occurring clays, and catalysts comprising specially prepared synthetic masses, for example, silica-alumina, silica-zirconia, silica-alumina-zirconia, and silica-alumina-thoria and similar refractory materials having a high degree of activity. These latter synthetic catalysts may be prepared by various methods such as mixing and coprecipitation of the various components under conditions whereby alkali metal ions are excluded. In these catalysts the ratio of the components may vary within wide limits and the masses may be considered to comprise intimate or possible molecular admixtures, all of the components indicating more or less low activity individually but in the aggregate displaying high activity. The activity also is not an additive function of the individual component, it being relatively constant for a wide range of proportions whether in molecular, or fractions of molecular proportions. It appears that no one component can be determined as the one component for which the remaining components may be considered as the promoter according to conventional terminology. In the present invention these catalysts are used in the form of sized particles or other formed shapes such as pellets produced by compression or extrusion methods. The pressed composites after drying and forming into definite shapes are calcined at temperatures

above 800° F., prior to contacting with the hydrocarbons.

The character of the catalysts described may vary somewhat depending upon the exact method of preparation and on the composition used. All of them have been found to have catalytic effect, but they are not necessarily exactly equivalent.

The conditions under which the catalytic cracking step is carried out may vary over the temperature range of approximately 800° F., to 1200° F. The amount of unconverted bottoms which are recycled will vary considerably and can be controlled according to the most efficient operation.

The amount and end point of the low-boiling gasoline used in the hydrogenation step is determined by the properties desired in the finished gasoline. Normally, olefinic hydrocarbons have relatively good antiknock properties but are not particularly susceptible to increase in octane number by the addition of antiknock agents. On the other hand, the paraffinic hydrocarbons have excellent tetraethyl lead susceptibility compared to the olefins. The highly branched iso-paraffins have higher antiknock properties than do the normal or straight-chain paraffins and also than the corresponding olefins. It is further known that hydrogenation of the octenes produced by polymerizing the butene fraction of the gases from catalytic cracking results in a saturated hydrocarbon mixture having a high octane number (95-100) as well as excellent blending value and lead susceptibility. On the other hand, the polymer obtained by polymerizing propylene has good octane number and blending value, but when hydrogenated the product loses desirable antiknock properties. The blending value of the polymer as produced, on the other hand, is good and tends to improve the octane number of a blend in which it is incorporated to a greater extent than would be predicted from its actual octane number as determined without blending. The present process takes advantage of the characteristic properties of the various types of gasoline produced and at the same time permits recirculation of high-boiling materials and the recovery of many of the gaseous products with the result that not only are the overall motor fuel properties of the gasoline improved, but the actual yield obtainable therefrom is increased substantially.

The polymerization steps of the process are carried out catalytically using catalysts such as the co-called solid phosphoric acid catalyst or sulfuric acid. The solid phosphoric acid catalyst is made by mixing a liquid phosphoric acid with kieselguhr or similar suitable siliceous material, forming into cylindrical or annular shapes, drying and calcining. The process is carried out at temperatures of approximately 275°-450° F., and pressures of 150-1000 pounds per square inch and up. Sulfuric acid polymerization may be carried out at temperatures within the range of 65°-250° F., with acid concentrations of 60% and higher.

The hydrogenation step may be carried out in the presence of catalysts such as nickel, copper, cobalt, chromium, iron, molybdenum sulfide, molybdenum oxide, etc., at temperatures of 250°-450° F., and pressures of approximately 15 to 1,000 pounds per square inch absolute depending on the stocks, the catalyst and the degree of hydrogenation desired. The hydrogen may be supplied from an external source or the gases

from the cracking process containing hydrogen may be used.

The accompanying drawing illustrates diagrammatically one embodiment of my process. It should be understood that the process is not limited to the exact apparatus or conditions specified therein. The drawing has not been made to any scale and neither has there been any attempt to represent the various pieces of equipment which compose the apparatus in exact proportion of one another.

Referring to the drawing, the oil enters the system through line 1, valve 2, valve 3, pump 4, line 5 and valve 6, passing into coil 7 which is disposed in furnace 8. By this means it is heated to a desired cracking temperature and passes through line 9 and valve 10 into catalytic converter 11 wherein a substantial portion is converted to gasoline and gas. The mixture passes through line 12 and valve 13 into fractionator 14 where it is divided into several portions. A portion of the unconverted oil boiling above the gasoline boiling range may be withdrawn through line 15 and valve 16, passed through line 17 and valve 18 into line 1 where it mingles with the raw charging stock and passes with it into the catalytic conversion stage. A portion of heavy bottoms may be withdrawn through line 19 and valve 20 to gas oil storage not shown. The mixed gasoline and gases pass through line 21 and valve 22 into stabilizer 23. A portion of high-boiling gasoline is withdrawn through line 24 and valve 25 to storage. A portion of the low-boiling gasoline is withdrawn through line 26 and valve 27 or through line 27' and valve 27' depending upon the end point desired in the side cut, into line 28 where it mingles with a desulfurizing reagent such as sodium hydroxide solution which may be pumped through line 29, valve 30, pump 31, valve 32 and line 33. The mixture of caustic and gasoline passes through mixer 34, line 35 and valve 36 into desulfurizer 37. The spent caustic is withdrawn through line 38 and valve 39 to caustic regeneration which is not shown. The desulfurizing step as employed herein is only one example of a method which may be used for desulfurizing the low-boiling gasoline. If so desired other desulfurizing solutions may be used instead of caustic soda such as ethanol amine, propanol amine, etc.; or solid desulfurizing materials may be used with suitable changes in apparatus. Such materials may comprise various metals, metal oxides or metal sulfides which have the property of combining with sulfur and sulfur compounds at relatively low temperatures. If it is desired to carry out the desulfurization step at low temperatures suitable heat exchange equipment may be introduced into line 26. The desulfurized gasoline passes through lines 40 and 41 and valve 42 to the hydrogenation step which will be described later. A part of the gasoline may be withdrawn to storage through line 40 and valve 41. The process gases from stabilizer 23 pass through line 43 and valve 44 through heat exchanger 45 by means of pump 45' and valve 45'' into sulfur removal system 46 by means of spray 47 where sulfur is removed by any well known method such as scrubbing with caustic, triethanol amine, and other well known desulfurizing methods. The desulfurizing medium enters the desulfurizer 46 by means of line 48, valve 49 and spray 50 where it passes downward counter-current to the upwardly flowing gases. The spent solution is withdrawn through line 51 and valve 52 to the regeneration system not shown. The

gases leave the desulfurizing step by means of line 53 and valve 54 and enter the separator 55 where they may be divided into various fractions. Separator 55 may suitably consist of a separate debutanizer and depropanizer but is shown as one vessel in the interests of simplifying the drawing. The C₄ fraction is withdrawn from the separator 55 by means of line 56, valve 57, pump 58, valve 59, heat exchanger 60, line 61, and valve 62 into the selective polymerization zone 63 and the products are discharged from the latter through line 64 and valve 65 to fractionator 66 where the unconverted butane and butene are removed through line 67 and valve 68. Alternative to this all or a portion of the unconverted gases may be passed through line 67' and valve 68' to join with line 100' and mingle therein with the C₃ fraction from separator 55. The polymer boiling above the gasoline boiling range may be withdrawn through line 69 and valve 70 and may be returned all or in part to the catalytic cracking step by means of line 71 and valve 72 which joins with line 17 and eventually with line 1. If so desired, a portion of the heavy polymer may be withdrawn through line 73 and valve 74 to storage. The C₈ polymer is withdrawn from fractionator 66 through line 75 and valve 76 which joins with line 41. The C₈ polymer and the low-boiling gasoline from line 41 mingle in line 77 and are pumped by means of pump 78 through valve 79 into line 80 where they mingle with the uncondensable gases from separator 55 which leave the separator through line 81, valve 82, pump 83 and valve 84. A portion of the hydrogen-containing gases may be withdrawn through line 81' and valve 81''. Under certain circumstances additional hydrogen may be added to the process through line 81' and valve 81''. The mixture passes through coil 85 which is disposed in furnace 86 where it is heated to the proper hydrogenation temperature and then passes through line 87 and valve 88 into the hydrogenator 89 which contains a suitable hydrogenation catalyst. The hydrogenated mixture leaves the plant through line 90 and valve 91, passing into stabilizer 92. The unused hydrogen as well as the low-boiling uncondensable gases are removed through line 93 and valve 94. The hydrogenated oil is removed through line 95 and valve 96 to storage. The C₃ olefins from separator 55 are removed through line 97, valve 98, pump 99 and valve 100, line 100' and valve 100'', passing into polymerizer 101 where the olefins are converted to the motor fuel boiling range. The reaction products pass through line 102, valve 103 into stabilizer 104. The substantially saturated gases are removed from the stabilizer by means of line 105 and valve 106. The polymer is removed through line 107 and valve 108 to storage. The finished products treated in the manner described which pass through lines 24, 73, 95 and 107 may be blended in whatever proportion is desired. Normally, the proportions are the same as those in which they are made. The end point of the material which may be withdrawn through line 73 is somewhat high, usually in the neighborhood of 425° F., and as a consequence only a limited amount of this can be used in the final blend. It is for this reason that the major portion of it is returned to the catalytic cracking zone. Furthermore, a portion of the low-boiling desulfurized gasoline from line 40 may be withdrawn through line 109 and valve 110 and blended with the final product. This permits control not only of the end point but also the amount of light

gasoline to be passed to the hydrogenation step, thus increasing the flexibility of the operation.

The method of operation of the plant can be varied somewhat from the preferred method as described. For example, the combined C₃ and C₄ olefins can be removed from the separator, polymerized, fractionated and hydrogenated if desired. In this case the C₃ and C₄ hydrocarbons are withdrawn from separator 55 through line 56, valve 57, pump 58, line 59, heat exchanger 60, line 61 and valve 62 into catalytic polymerizer 63. No product is withdrawn from separator 55 through line 91 or valve 98. In this case polymerizer 101 is not used.

15 The following example is given to illustrate my process and should not be considered as limiting it to the exact conditions given therein.

A Mid-Continent gas oil of 35.9° A. P. I. gravity was catalytically cracked at a temperature of 975° F. The unconverted bottoms were recycled to the catalytic cracking step. The gas and gasoline were removed from the fractionator and separated into (a) gases containing C₄ and lighter hydrocarbons, (b) a 300° F. end point cracked gasoline, and (c) a higher boiling cracked naphtha fraction. The low-boiling cracked gasoline was treated with approximately 10% of 30 Bé. caustic solution and passed as described in the foregoing specification to the hydrogenation step. The gases were scrubbed continuously by means of triethanolamine solution whereby they were desulfurized, and separated into a low-boiling fraction containing hydrogen, methane, ethane and ethylene which was passed to the hydrogenation step, a propane-propylene fraction which was passed to a non-selective polymerization step, and a butane-butene fraction which was passed to a selective polymerization step where, by means of a solid phosphoric acid catalyst, the olefins were largely converted to liquid polymers. The iso-octenes were recovered and combined with the 300° F. end point catalytically cracked gasoline and the hydrogen-containing gases and passed into the hydrogenation step with nickel catalyst operating at 15 pounds per square inch pressure and 400° F., the product recovered and later blended with the finished gasoline. The residual gases from the selective polymerization step contained an appreciable amount of unconverted normal butene and were combined with the propane-propylene fraction of the catalytically cracked gases and passed to a separate polymerization step. The polymer was recovered and blended with the finished gasoline. The high-boiling polymers from the polymerization plants were recirculated to the catalytic cracking step. The final blend of gasoline consisted of a mixture of catalytically cracked naphtha, the hydrogenated low-boiling fraction of cracked gasoline and iso-octane, and polymer gasoline. The resulting blend had an octane number of 84 which was increased by 3 cc. of tetraethyl lead solution to 93. The total yield of gasoline amounted to 87.5%. The operation involving only catalytic cracking and nonselective polymerization of the C₃ and C₄ olefins resulted in a yield of approximately 82% of gasoline having an octane number of 81. The susceptibility of this gasoline to tetraethyl lead was less than that of the gasoline from the present process having with 3 cc. of lead, an 88 octane number.

I claim as my invention:

1. A process which comprises contacting hydrocarbon distillate with a cracking catalyst at catalytic cracking conditions, separating the gas

and gasoline, separating the gasoline into a low-boiling and a high-boiling fraction, separating the gaseous products into a plurality of fractions, one of which comprises essentially hydrogen and uncondensable hydrocarbon gases, and another a fraction comprising essentially C₃ and C₄ hydrocarbons, catalytically polymerizing the C₃ and C₄ olefins in said fraction, combining the polymers thereof boiling within the gasoline boiling range with the aforesaid low-boiling fraction of gasoline from the catalytic cracking step and the hydrogen-containing gas from the cracking step, contacting said mixture with a hydrogenating catalyst at hydrogenating conditions, recovering the hydrogenated product, and blending it with the high-boiling gasoline fraction from the catalytic cracking step.

2. A conversion process which comprises cracking catalytically hydrocarbon oil to produce olefinic gasoline, gaseous olefins and hydrogen, fractionating the resultant products and separating therefrom a heavy gasoline fraction, a light gasoline fraction, a butene-containing normally gaseous fraction and a hydrogen-containing gas,

subjecting said butene-containing fraction to polymerization to convert butenes to octenes, combining the latter with said light gasoline fraction and with at least a portion of said hydrogen-containing gas, subjecting the resultant mixture to hydrogenating conditions, and recovering the saturated gasoline boiling hydrocarbons thus produced.

3. A conversion process which comprises catalytically cracking hydrocarbon oil to produce olefinic gasoline, gaseous olefins and hydrogen, fractionating the resultant products and separating therefrom a heavy gasoline fraction, a light gasoline fraction, a butene-containing normally gaseous fraction and a hydrogen-containing gas, subjecting said butene-containing fraction to polymerization to convert butenes to octenes, combining the latter with said light gasoline fraction and with at least a portion of said hydrogen-containing gas, subjecting the resultant mixture to hydrogenating conditions, and blending the saturated gasoline boiling hydrocarbons thus produced with said heavy gasoline fraction.

CHARLES L. THOMAS.
